BUILDING PANEL FOR ROOFS AND THE LIKE

Victor F. Christ-Janer, Frogtown Road,
New Canaan, Conn.

Filed Dec. 13, 1962, Ser. No. 72,845

Term of patent 14 years

(Cl. D13—1)

FIG. 1

FIG. 2

FIG. 3

FIGURE 1 is a top perspective view of a building panel for roofs and the like showing my new design;

FIGURE 2 is a bottom perspective view of the building panel for roofs and the like of FIGURE 1;

FIGURE 3 is a cross-sectional view of the building panel for roofs and the like taken at 3—3 of FIGURE 1.

I claim:

The ornamental design for a building panel for roofs and the like, as shown.
